DERIVATIVES OF 3-AZA-BICYCLO (3:2:0)
HEPTANE-2,4-DIONE

Charles H. Grogan, Falls Church, Va., and Leonard M. Rice, Baltimore, Md., assignors to The Geschickter Fund for Medical Research, Inc., Washington, D. C., a corporation of New York

No Drawing. Application October 10, 1955,
Serial No. 539,653

11 Claims. (Cl. 260—247.5)

This invention relates to compositions of matter, particularly to chemo-therapeutic organic compounds that are also of value as synthetic and pharmaceutical intermediates in preparing other chemo-therapeutic agents. More particularly the invention relates to compounds possessing bronchodilatory, antispasmodic and local anesthetic properties in varying degrees.

Specifically this invention relates to dialkylaminoalkyl imides of 1,2-cis-cyclobutane dicarboxylic anhydride, their simple and quaternary salts.

It is a basic object of the present invention to provide novel organic compounds and methods for the preparation thereof.

It is another object of the invention to provide novel, physiologically active compounds characterized by chemotherapeutic or medicinal properties, particularly bronchodilatory, antispasmodic and local anesthetic activity.

These and other objects and the manner in which they are accomplished will become apparent to those conversant with the art from the following description of the general class of compounds and certain specific examples of particular members thereof as well as general and specific methods of their preparation.

Generally stated, the novel compounds discovered are obtained by reacting the appropriate dialkylaminoalkylamine with the anhydride of 1,2-cis-cyclobutane dicarboxylic acid to form the intermediate amic acid which is cyclized to the imide by heating for 2 hours at 170–180° C. The imides are isolated directly from the reaction mixture by vacuum distillation and are then converted to simple or quaternary salts by reaction with an acid or an alkyl halide respectively in suitable media.

Formula 1

Formula 1 shows the general structural formula of compounds obtained by the methods hereafter more particularly described. This formula illustrates the imides and for convenience in presentation the azabicycloheptanedione nucleus (enclosed in parenthesis, Formula 1) will be designated by the letter A hereafter.

Formula 2

The simple salts of these imides, formed on the side chain nitrogen are illustrated by Formula 2, and the

2

monoquaternary salts, likewise formed on the side chain nitrogen are illustrated by Formula 3.

Formula 3

In these formulae A represents the azabicycloheptanedione nucleus, n a number from 1 to 6, R represents 2 alkyl groups with from 1 to 6 carbon atoms, and R' an alkyl group with from 1 to 6 carbon atoms or an alkylene group containing 3 carbon atoms. The structure (N=R) may represent a heterocyclic ring namely, morpholine, piperidine, pyrrolidine, piperazine or N-methyl piperazine. X- represents an anion, namely, chloride, iodide, bromide, acetate or sulfate. In the quaternary salts R' may be the same as or different from R in any of the formulae given.

The following examples of specific compounds and methods of their preparation will illustrate the manner in which they are obtained by the application of the general synthesizing procedure to particular members of the class of compounds discovered. It will be understood, however, that the following examples are merely illustrative and are not, nor are they intended to be, exhaustive of all the compounds embraced by this invention.

EXAMPLE I

30 N - dimethylaminoethyl - 3 - azabicyclo(3:2:0)heptane-2,4-dione simple salts and quaternary salts

The imide.—0.2 mole of 1,2-cis-cyclobutane dicarboxylic anhydride was weighed into a 50 ml. 24/40 flask and 0.2 mole of dimethylaminoethylamine added rapidly in one lot. An exothermic reaction took place and the mass soon liquified. It was stirred until homogeneous (or heated if necessary to obtain a homogeneous liquid phase) and reweighed. Any amine lost (usually none) was replaced and a 1–2% excess of amine added. The reaction mixture was stirred until again homogeneous and heated slowly to 170–180° C. It was maintained at this temperature until water was no longer evolved (usually 2 hours) to cyclize the amic acid initially formed to the imide. Following the heating period, the flask was connected directly to a vacuum distillation apparatus and heated slowly to the boiling point so as to remove any lower boiling material such as unreacted amine. The material was distilled and the whole distilled between 114–116° C./1 mm. It was redistilled and there was obtained 26.5 grams of imide, B. P. 86–94° C./0.08 mm. as a clear, colorless, oily liquid, $n_{D}^{20} = 1.4938$.

	Carbon, Percent	Hydrogen, Percent	Nitrogen, Percent
Calculated.....	61.20	8.22	14.28
Found.....	61.32	8.24	14.32

The monohydrochloride.—This was obtained as a white crystalline material by adding an excess of an ethanol solution of HCl to the amide dissolved in a minimum amount of isopropanol and precipitation with anhydrous ether. It had a melting point of 204–205° C. Recrystallization from isopropanol gave a melting point of 204.5–205.5° C.

Ionic chloride: Calculated—15.24%; found—15.23%.

The monomethiodide.—The monomethiodide was obtained as a white crystalline material by adding a slight excess of methyl iodide to the imide dissolved in acetone. It melted at 257–259° C. Recrystallization from

3

absolute ethanol increased the melting point to 259–260° C.

Ionic iodide: Calculated—37.53%; found—37.31%.

EXAMPLE II

N - diethylaminoethyl - 3 - azabicyclo(3:2:0)heptane-2,4-dione simple and quaternary salts

The imide.—This imide was prepared in a manner analogous to that detailed under Example I by the reaction of 0.2 mole of diethylaminoethylamine with 0.2 mole of the anhydride. On vacuum distillation 29 grams of a colorless oily liquid, B. P. 93–100° C./0.2 mm. was obtained, $n_D^{20}=1.4910$.

	Carbon, Percent	Hydrogen, Percent	Nitrogen, Percent
Calculated.....	64.25	8.90	12.49
Found.....	64.44	8.83	12.60

The monohydrochloride.—Obtained from the imide as detailed under Example I as a white crystalline material, M. P. 203–204° C. The material crystallized from isopropanol in hexagonal plates, M. P. 204–205° C.

Ionic chloride: Calculated—13.60%; found—13.69%.

The monomethiodide.—Obtained from the imide as detailed under Example I as a white crystalline material, M. P. 125–126° C. that did not change on recrystallization.

Ionic iodide: Calculated—34.65%; found—34.81%.

EXAMPLE III

N-dimethylaminopropyl-3-azabicyclo(3:2:0)heptane-2,4-dione simple and quaternary salts

The imide.—Reaction of 0.2 mole of dimethylamino-

4

pyrrolidine with 0.1 mole of the anhydride as detailed under Example I yielded 16.6 grams of the title imide, B. P. 100–103° C./0.1 mm., $n_D^{20}=1.4918$.

5		Carbon, Percent	Hydrogen, Percent	Nitrogen, Percent
Calculated.....	65.51	9.31	11.76	
Found.....	65.63	9.21	12.01	

10 *The monohydrochloride.*—This was formed from the imide in isopropanol with an excess of alcoholic-HCl and precipitation with ether, M. P. 149–151° C. not changed on recrystallization.

15 Ionic chloride: Calculated—12.90%; found—13.10%.

The monomethiodide.—This was formed from the imide in acetone with a slight excess of methyl iodide, M. P. 184–185° C. not changed on recrystallization.

Ionic iodide: Calculated—33.37%; found—33.43%.

20

EXAMPLE V

N-morpholinopropyl-3-azabicyclo(3:2:0)heptane-2,4-dione simple and quaternary salts

25 *The imide.*—This was formed by reaction of 0.1 mole of morpholinopropylamine with 0.1 mole of the anhydride as detailed under Example I. Obtained 21.1 grams, B. P. 150–155° C./0.3 mm., $n_D^{20}=1.5130$.

The monohydrochloride.—This was formed from the imide in isopropanol with alcoholic-HCl and precipitation with anhydrous ether as a white crystalline material, M. P. 236–237° C. Recrystallization from isopropanol, M. P. 238–239° C.

Ionic chloride: Calculated—14.37%; found—14.51%.

EXAMPLE IV

N-diethylaminopropyl-3-azabicyclo(3:2:0)heptane-2,4-dione simple and quaternary salts

The imide.—Reaction of 0.1 mole of diethylaminopro-

60 *The monohydrochloride.*—This was formed from the imide in isopropanol with excess alcoholic-HCl and was a white crystalline material, M. P. 182–3° C. Recrystallized from isopropanol-ethyl ether, M. P. 185–186° C.

Ionic chloride: Calculated—12.28%; found—12.31%.

65 *The monomethiodide.*—This was formed from the imide in acetone with a slight excess of methyl iodide, and was a white crystalline material, M. P. 236–238° C. decomposition. Recrystallized from isopropanol, M. P. 239.5–241° C. decomposition.

Ionic iodide: Calculated—32.19%; found—32.12%.

From the foregoing description of a novel class of compounds, details of preparation and characterization of exemplary members of the class, it will be understood that, on the basis of the discovery and knowledge dis-

70 closed herein, other specific compounds can be made and variations in the methods of synthesis resorted to. The appended table contains additional examples of imides prepared by the procedures detailed herein. Therefore, the specific compounds and methods disclosed herein are 75 to be considered in all respects as illustrative and not re-

strictive, the scope of the discovery being indicated by the appended claims rather than the foregoing descriptive detailed examples, and all specific compounds and variations and methods which come within the meaning and range of equivalency of the claims are therefore intended to be embraced therein.

What is claimed and desired to be secured by United States Letters Patent is:

1. As a novel composition of matter, a compound selected from the group consisting of (1) compounds having the formula

where, in said formula, n is a number from 1 to 6, and R is selected from the group consisting of two alkyl groups with each alkyl group having from 1 to 6 carbon atoms and radicals which form, together with the nitrogen atom to which they are attached, a heterocyclic group selected from the group consisting of morpholino, piperidino and pyrrolidino, and (2) the acid addition salts and mono-quaternary salts of (1).

2. As a novel composition of matter, a mono-methonium salt of N-dimethylaminoethyl-3-azabicyclo(3:2:0)-heptane-2,4-dione.

3. As a novel composition of matter, a mono-metho-

nium salt of N-dimethylaminoethyl-3-azabicyclo(3:2:0)-heptane-2,4-dione.

4. As a novel composition of matter, a mono-methonium salt of N-dimethylaminopropyl-3-azabicyclo(3:2:0)-heptane-2,4-dione.

5. As a novel composition of matter, a mono-methonium salt of N-diethylaminopropyl-3-azabicyclo(3:2:0)-heptane-2,4-dione.

6. As a novel composition of matter, a mono-methonium salt of N-morpholinopropyl-3-azabicyclo(3:2:0)-heptane-2,4-dione.

7. As a novel composition of matter, N-dimethylaminoethyl-3-azabicyclo(3:2:0)heptane-2,4-dione.

8. As a novel composition of matter, the mono-methonium chloride of N-dimethylaminoethyl-3-azabicyclo(3:2:0)heptane-2,4-dione.

9. As a novel composition of matter, N-diethylaminoethyl-3-azabicyclo(3:2:0)heptane-2,4-dione.

10. As a novel composition of matter, the mono-methonium chloride of N-diethylaminoethyl-3-azabicyclo(3:2:0)heptane-2,4-dione.

11. As a novel composition of matter, the mono-methonium chloride of N-dimethylamino-propyl-3-azabicyclo(3:2:0)heptane-2,4-dione.

UNITED STATES PATENT OFFICE
CERTIFICATE OF CORRECTION

Patent No. 2,802,004

August 6, 1957

Charles H. Grogan et al.

It is hereby certified that error appears in the printed specification of the above numbered patent requiring correction and that the said Letters Patent should read as corrected below.

Column 2, line 63, for "amide" read -- imide --; column 6, line 1, for "N-dimethylaminoethyl-3-" read -- N-diethylaminoethyl-3- --.

Signed and sealed this 26th day of November 1957.
